UNITED STATES PATENT OFFICE.

FRANK THILOW, OF PHILADELPHIA, PENNSYLVANIA.

CIGAR-LIGHTER.

1,369,144.

Specification of Letters Patent. Patented Feb. 23, 1921.

Application filed July 9, 1919. Serial No. 309,776.

To all whom it may concern:

Be it known that I, FRANK THILOW, a citizen of the United States, residing at Philadelphia, in the county of Philadelphia and State of Pennsylvania, have invented 5 new and useful Improvements in Cigar-Lighters, of which the following is a specification.

My invention relates to a new and useful 10 improvement in cigar lighters, and has for its object to provide an exceedingly simple and effective device of this description in which a generator is utilized for automatically producing gas from diluted sulfuric 15 acid and zinc, and storing said gas from which storage it may be drawn and ignited by contact with the platinum sponge, and

A further object of my invention is to so 20 locate a mirror relative to the burner of the device as to reflect the end of the cigar being lighted, thus greatly facilitating this process.

With these ends in view, this invention 25 consists in the details of construction and combination of elements hereinafter set forth and then specifically designated by the claims.

In order that those skilled in the art to 30 which this invention appertains, may understand how to make and use the same, I will describe its construction in detail, referring by numerals to the accompanying drawings forming a part of this application, in which:—

Figure 1, is a perspective of a cigar lighter 35 made in accordance with my improvement.

Fig. 2, is a central vertical section of Fig. 1, and

Fig. 3, is a section at the line 3—3 of Fig. 2.

In carrying out my invention as here embodied, 1 represents a container, here shown 40 in the form of a glass jar having a top or cover 2 adapted to be threaded over the mouth of the bottle and be sealed by the 45 compressible packing ring 3.

4 represents a burner which is provided with a shank 5 passing through the cover, and to this shank is secured the neck 6 of the gas reservoir 7 by cement as at 8, or in 50 any other suitable manner. This reservoir is here shown as being made in the shape of a bottle without a bottom so that when immersed in the liquid 9 in the container it 55 acts as a gasometer and prevents the rising of the liquid therein so long as the outlet through the top thereof is closed.

10 represents a zinc plate suspended by the rod 11 from the shank 5.

12 represents the valve fitted within the top of the burner so as to control the out- 60

flow of gas from the reservoir 7 through the passageway 13 and this valve has secured thereon the hand lever 14 which latter is provided with an extension 15 having a

coiled spring 16 attached to its outer end, 65 while the inner end of said spring is attached to the eye 17 on the top of the cover.

By this construction the valve 12 will be normally held in its closed position so as to prevent the outflow of gas from the reser- 70

voir, but when it is desired to produce a flame the depression of the hand lever 14 will revolve the valve to permit the gas to flow from the reservoir 7, the liquid 9 in the container gradually rising in the reser- 75

voir as the gas escapes from the latter, as will be readily understood. This rising of the liquid in the container will bring said liquid into contact with the zinc plate 10 and

as this liquid attacks the zinc to form a gas 80 the liquid will be forced out of the bottom of the container so as to carry it out of contact with the zinc, and thus automatically

regulate the formation of the gas.

18 represents an inverted cap or housing 85 in which the proper amount of platinum sponge 19 will be held in such manner as to be protected against undue moisture and thus be permitted to remain in its active

state. The manipulation of the valve to 90 permit the gas to flow from the burner will project said gas into the cap 18 against the platinum sponge 19, which contact as is well

known will rapidly raise the temperature of the platinum sponge to the point of igniting 95 the gas thus producing a flame from which

the gas may be lit.

The cap 18 carries a lug 20 through which the rod 21 passes, a set screw 22 being provided for holding this cap in any adjustment upon this rod.

The lower end of the rod 21 is secured in the boss 23 carried upon the top of the cover. This arrangement permits the adjustment of the platinum sponge to or away from the 105 tip of the burner so as to increase the length of the frame and give greater or less space for access thereto.

Heretofore it has been both awkward and difficult for a smoker to determine when a 110 proper light has been secured upon the end of the cigar, and this difficulty I have en-

tirely overcome by combining a mirror 24 with the device and I have here shown this mirror as being provided with a shank 25 carrying a slip socket 26 which is adapted 5 to run upon the post 27 projecting upward from the top of the cup. This permits of the vertical adjustment of the mirror as well as its sidewise adjustment since the slip joint may be raised or lowered upon its post 10 or said joint may be turned upon its axis so as to set the mirror at different angles. This mirror is so located that a person lighting a cigar will be enabled to observe the end of said cigar when in contact with the flame 15 and thus a proper light may be obtained and this is of great importance since the improper lighting of a cigar deteriorates the smoking quality thereof causing it to burn unevenly and smoulder giving a disagreeable 20 odor and taste.

Of course I do not wish to be limited to the exact details of construction as herein shown as these may be varied within the limits of the appended claims without departing from the spirit of my invention.

Having thus fully described my invention, what I claim as new and useful is:—

1. A cigar lighter comprising a container having an externally threaded neck, a 30 threaded top run upon said neck, a compressible washer interposed between the lower flange of the top and a flange formed upon the neck of the container, a burner having a shank projecting through the top,

a reservoir secured to said shank, said reservoirs being open at the bottom, a boss carried by the top, a rod the lower end of which is secured in said boss, a platinum holding cap, a lug formed with said cap, said lug having a hole therethrough for the passage 40 of the upper end of said rod, and a set screw for holding the cap in various adjustments upon said rod.

2. A cigar lighter comprising a container having an externally threaded neck, a 45 threaded top run upon said neck, a compressible washer interposed between the lower flange of the top and a flange formed upon the neck of the container, a burner having a shank projecting through the top, 50 a reservoir secured to said shank, said reservoirs being open at the bottom, a boss carried by the top, a rod the lower end of which is secured in said boss, a platinum holding cap, a lug formed with said cap, said lug 55 having a hole therethrough for the passage of the upper end of said rod, and a set screw for holding the cap in various adjustments upon said rod, a valve fitted in the burner for controlling the outflow of gas from the 60 reservoir, a hand lever carried by said valve for operating the latter, an extension formed with said lever, and a coil spring connecting the outer end of said extension with the cover.

In testimony whereof I have hereunto affixed my signature.

FRANK THILOW.
